UNITED STATES PATENT OFFICE.

FRANK CAMERON, JR., OF HARRISON, OHIO, ASSIGNOR OF ONE-THIRD TO ALBERT C. KNEFFLE, OF HARRISON, OHIO.

SHAPE-RETAINER FOR THE BOTTOMS OF TROUSERS-LEGS.

1,381,965.

Specification of Letters Patent. Patented June 21, 1921.

Application filed July 12, 1920. Serial No. 395,572.

To all whom it may concern:

Be it known that I, FRANK CAMERON, Jr., citizen of the United States, residing at Harrison, in the county of Hamilton and 5 State of Ohio, have invented certain new and useful Improvements in Shape-Retainers for the Bottoms of Trouser-Legs, of which the following is a specification.

This invention has as its object to provide 10 a novel means for retaining the shape of the bottoms of trouser legs whether the same be plain or of the cuff type, the means being designed, by reason of its presence within the leg bottoms, to maintain the lower portion 15 of the trouser legs in the shape in which they are initially pressed and likewise to protect the lower edge of the bottoms from becoming worn through frictional contact with the shoe.

20 Another object of the invention is to provide a device for the purpose stated which may be readily applied by any one and which when applied will not be visible.

A further object of the invention is to provide 25 a device for the purpose stated so constructed that it will be flexible to a certain degree so that the trouser leg bottoms may be permitted to assume their natural position draped over the shoe uppers, and yet, as 30 previously stated, the shape of the trouser leg bottoms will be maintained because of the presence of the device.

Still another object of the invention is to so 35 construct the device that when the same is applied by stitching it to the trouser leg bottoms, the stitches will be protected from contact with the shoe uppers and will not, therefore, be liable to become worn.

Also, the invention has as an object to so 40 construct the device that the same will not permit the trouser leg bottoms to sag and expose the device to view.

In the accompanying drawing:

Figure 1 is a view illustrating a trouser 45 leg bottom equipped with the device, the trouser leg bottom being shown in side elevation and a portion being broken away so as to illustrate a portion of the device also in elevation.

50 Fig. 2 is a view looking at the inner side of the trouser leg with the device applied, the material of the leg being spread open so as to better disclose the arrangement of the device within the bottom of the leg.

Fig. 3 is a vertical transverse sectional view on the line 3—3 of Fig. 2.

Fig. 4 is a horizontal sectional view on the line 4—4 of Fig. 1.

In the drawing, the numeral 1 indicates in 60 general a trouser leg bottom provided with a cuff 2, although it will be understood that the device embodying the present invention is applicable to trouser leg bottoms which are of plain construction as well as to bottoms which are provided with cuffs.

65 The device embodying the present invention is preferably made of soft or semi-soft rubber although if found desirable some other material may be employed for the purpose. The device is indicated in general by 70 the numeral 3 and the same comprises a strip-like body 4 which may have its ends tapered as indicated by the numeral 5, if desired. This body 4 is either formed by a direct molding operation, or during the course of 75 manufacture it is folded upon itself between its ends and the two side portions thus formed are vulcanized or otherwise united for a short distance so as to provide a well defined relatively thin crease retaining portion 80 6 which is located at the front of the device, and which is most clearly shown in Fig. 4 of the drawing.

85 For a purpose to be presently explained, the body 4 of the device is formed with an integral upstanding bracing portion 7 which is located to one side of the crease retaining portion 6 as best shown in Figs. 2 and 4 of the drawings. This portion 7 may, if desired,

90 like the ends of the body 4, be tapered or brought to a point as indicated by the numeral 8 and it will be evident by reference to these figures that when the device is disposed

95 within the bottom of the trouser leg, in proper position, the crease retaining portion 6 will seat within the rear crease in the trouser leg bottom, and the side portions of

the device, which normally assume a slightly divergent relation due to the inherent resiliency of the material from which the device 100 is formed, will extend along the inner surfaces of the opposite sides of the trouser leg bottom near the lower edge thereof, the bracing and reinforcing portion 7 projecting upwardly beside the inner surface of one side 105 of the trouser leg bottom so as to prevent overturning or curling up of the trouser leg bottom which might result in exposure of the

device and which would also result in disarrangement or distortion of the cuff or plain bottom to such an extent as to render the same unsightly.

5 In order that the device above described may be secured to the inner side of the trouser leg bottom, it is preferable that the body 4 and the upward extension 7 be formed along their margins with a continuously extending channel which is indicated by the numeral 9 and which may be molded in the inner face of the device at the time of manufacture. A line of stitching 10 is to be run through the body 4 and its extension 7 and through the trouser leg bottom for the purpose stated, and these stitches will be located within the channel 9 and will, therefore, not be exposed at the surface of the device and so cannot come into rubbing contact with the shoe upper which contact would under other conditions result in the stitches becoming worn through.

From the foregoing description of the invention it will be understood that the device 25 may be readily applied to any trouser leg bottom and that when in place it will serve to maintain the trouser leg bottom in its proper pressed shape. It will also be evident that the crease retaining portion 6 will 30 serve effectually to maintain the rear crease in the trouser leg bottom and that the up-

ward extension 7 of the device will serve effectively to prevent the trouser leg bottom turning up at the rear so as to expose the device.

35

While the device is preferably applied by stitching, it is understood that it may be applied by adhesive if found desirable.

Having thus described the invention, what is claimed as new is:

40

1. A shape retainer for the bottoms of trouser legs comprising a strip-like body shaped to seat within the creased portion of the bottom of the trouser leg and to extend along the opposite sides of the said bottom, 45 the said body being provided with an upwardly extending bracing and reinforcing portion and being formed in its inner face and in the inner face of its said upwardly extending portion with a marginally extending channel to receive and house stitches which are to secure the device to the trouser leg bottom.

50

2. A shape retainer for the bottoms of trouser legs comprising a strip-like body provided with a fold between its ends to form spaced side portions, and an integral bracing portion upstanding from the upper edge of one of the side portions in the plane thereof and relatively close to the said fold. 60

55

In testimony whereof I affix my signature.
FRANK CAMERON, JR. [L. S.]
